(57) **CLAIM**

The ornamental design for a dispenser vessel, as shown and described.

DESCRIPTION

FIG. 1 is a side perspective view of a dispenser vessel in accordance with the present design;

FIG. 2 is a bottom perspective view of the dispenser vessel;

FIG. 3 is a front view of the dispenser vessel;

FIG. 4 is a rear view of the dispenser vessel;

FIG. 5 is a side view of the dispenser vessel;

FIG. 6 is another side view of the dispenser vessel;

FIG. 7 is a top view of the dispenser vessel;

FIG. 8 is a bottom view of the dispenser vessel;

FIG. 9 is a top perspective view of a base of the dispenser vessel;

FIG. 10 is a bottom perspective view of the base of the dispenser vessel;

FIG. 11 is a front view of the base of the dispenser vessel;

FIG. 12 is a rear view of the base of the dispenser vessel;

FIG. 13 is a side view of the base of the dispenser vessel;

FIG. 14 is another side view of the base of the dispenser vessel;

FIG. 15 is a top view of the base of the dispenser vessel; and,

FIG. 16 is a bottom view of the base of the dispenser vessel.

The broken lines in the drawings depict portions of the dispenser vessel that form no part of the claimed design.
